LEVEL AND DRAINAGE PROJECTION
INSTRUMENT

Edgar T. Kemp, Premont, Tex.

Application August 21, 1935, Serial No. 37,233

2 Claims. (Cl. 33—73)

The invention relates to an instrument of the type resembling surveying instruments but designed for production at a very reasonable cost, and adapted to be used by persons not familiar with the profession of surveying to enable projecting levels and also inclination for the purpose of drainage and the like, the instrument being extremely simple in construction and requiring a minimum of practice to enable the operator to successfully use the instrument.

The invention will be described in detail hereinafter and will be found illustrated in the accompanying drawing, in which

Figure 1 is a rear view in elevation of the level and drainage projecting instrument showing the supporting tripod fragmentarily,

Figure 2 is an end view in elevation of the parts shown in Figure 1,

Figure 3 is a top plan view, and

Figure 4 is a transverse sectional view on a plane indicated by the line 4—4 of Figure 2.

Referring to the drawing in which similar reference characters are used to designate corresponding parts in all the views, the instrument is provided with the conventional tripod head 10 having blades 11 on which are pivotally mounted the legs of the tripod support 12, said legs being bifurcated at their upper ends as shown at 13 to receive the blades 11 and to be pivotally mounted thereon by means of bolts or pivot pins 14.

The head 10 extends above the upper edges of the blades 11 as shown at 15, and has its upper edge curved as shown at 16. Pivotally mounted on the extension 15 is a U-shaped member 17 by means of a pivot pin or bolt 18, said U-shaped member having upwardly extending and spaced arms 18'. Said U-shaped member and the upwardly extending arms 18' are preferably made in one piece of relatively thin metal and the metal may be of resilient type to permit the sides of the U-shaped member being pressed inwardly against the extension 15 when a part is adjusted thereon, by tightening the nut on the bolt 18, and the arms 18' may also be tightened on the part to be hereinafter described to hold said part in its adjusted position relatively to the arms.

A table member is mounted between the arms 18' and consists of a T-shaped structure as clearly shown in Figure 3 having a rearwardly extending portion 20 that is mounted between the arms 18' on a pivot pin or bolt 21. Secured at one end of the rearwardly extending portion 20 are laterally extending arms 22, said portions 20

and arms 22 forming a substantially T-shaped table member as hereinbefore described.

The parts 20 and 22 are held together by means of straps 23 and angle braces or straps 24 so that the top edges of the portions 20 and 22 will be on the same level.

To enable ascertaining whether the table portion 19 is level after it is set up on the tripod base as hereinbefore described, spirit level elements 25 are provided in each of the arms 22 and in portion 20, it being apparent that by moving the portion 20 on the pivot pin 21 the level may be obtained in one direction as indicated by the level elements 25 in said portion 20, and then by adjusting the table on the other pin 18 the level may be obtained in the direction transverse to the level already secured through movement on the pivot pin 21, and when a proper level has been obtained, the three level elements 25 should simultaneously indicate zero on the level instrument.

At opposite ends of the arms 22 are secured upright supporting members 26 having openings 27 therein at selected distances from the upper edge of the arms 22, and secured in the uppermost of said openings 27 and connecting the members 26 is a thread 28, said thread being parallel with the upper surface of the table member 19, that is of the arms 22. Also connected to the members 26 are other threads that are inclined to the level of the surface of the table 19, and as shown in the drawing, one of said threads designated 29, is secured in the left hand member 26 at the same point as the thread 28, the other end of said thread 29 being secured on the member 26 in the opposite end of the table at a distance below the point of connection of the thread 28, this distance being determined by the fall necessary for drainage of the land to be surveyed. There is also shown a third thread 30 that inclines in the opposite direction to the thread 29 connecting the two members 26, and may be as shown in the drawing connected to one member 26 at the same point as the lower end of the thread 29, and to the opposite member 26 adjacent to the upper surface of the table 19, or any other position may be used for this thread as may be found necessary for the purpose for which the instrument is to be used.

Secured to the free end of the portion 20 of the table is an upright member 31 that has openings 32 therein that are used as sight openings by the user of the instrument, the operator utilizing the threads 28, 29 or 30, as the case may be or any other arrangement of threads that might

be substituted therefor to obtain the drainage of the land that is surveyed by means of the instrument.

The tripod head 10 is provided with the usual plumb-bob 33 hung on the cord 34 therefrom for use in setting up the tripod.

It will be apparent that by using the uppermost sight opening 32 in the member 31, the condition of the land being surveyed by means of the instrument as to level may be readily determined by using a conventional surveyor's rod or other like implement for marking the land as it is surveyed, and the land may also be marked by means of the surveyor's rod by sighting on the thread 29 to drain the land from position to the left of the instrument downwardly toward the right, or if drainage is to be obtained in the opposite direction then the position of the thread 29 must be altered accordingly. The lowermost opening 32 in the member 31 may be used for sighting along the thread 30 for drainage in the opposite direction from the lowermost point where surveyed by using the thread 29.

It will also be understood that the contour of a terrace, levee, dam or the like, may be instantaneously projected either for a level or on an incline by means of the instrument and pegs be driven by an assistant as directed by the surveyor to indicate the lines projected without the necessity of use of a surveyor's rod as above stated. Also that preliminary surveys for contour lines or for inspections for repairs or alterations can be made by the surveyor without assistance. Furthermore that the definite, fixed

location of the instantaneous projection is a safeguard against errors. For convenience, begin surveys from levels below the lines to be traced stationing the instrument below the line of the desired survey.

5

What is claimed is:—

1. A level and drainage projecting instrument, comprising a table having aligned portions and a lateral portion extending therefrom midway of the outer end of the aligned portion, means connected to said lateral portion mounting said table to swing it on pivots arranged at right angles to one another, an upright arm on said lateral portion having a sight opening therein, upright arms on said aligned portions and spaced from one another, a thread connecting the last mentioned arms and arranged parallel to the table top, and another thread connecting said last mentioned arms and secured to one of said arms at a point coincident with the first mentioned thread and secured to the other upright at a point below said parallel thread.

2. A level and drainage projecting instrument, comprising a table having aligned portions and a lateral portion extending therefrom at a location mid-way of the ends of the aligned portions, means connected to said lateral portion mounting said table to swing it on pivots arranged at right-angles to one another, an upright arm on said lateral portion having a sight opening therein, upright arms on said aligned portions spaced from one another, and a thread connecting the last mentioned arms.
